ATTORNEY

UNITED STATES PATENT OFFICE

ALFRED CHARLES ATKINS, OF LONDON, ENGLAND

SUITCASE

Application filed August 22, 1927, Serial No. 214,730, and in Great Britain September 25, 1926.

- This invention relates to variable capacity boxes, suit cases, trunks and the like of the type comprising a top portion or cover coming over a lower or box portion and having extensible hinges and fastening devices adapted to be locked in any position, secured to the front and rear walls of the portions so that the box, suit case, trunk or the like may be locked when closed in any extended position.
- 10 In general, boxes, cases, trunks or the like of the above type constructed according to the invention have the top portion or cover of rectangular vertical cross section from front to back. The lower or box portion has a rectangular base and a rear wall at right angles thereto. A short distance upward from the base, this rear wall is stepped inwards to a slight extent and then proceeds upwards parallel to the first portion at right angles to the base. The front wall of the lower or box portion is at right angles to where it joins the base and for a short distance up and then it inclines or curves slightly towards the rear wall, the inclination or curvature increasing if desired towards the upper edge. When the portions are assembled together to give the minimum capacity the lower edge of the rear wall of the cover portion comes just above the step on the rear wall of the box portion and the depth of the step is such that the outer exposed surfaces of the rear walls come in the same plane which is at right angles to the top and base of the box, case, trunk or the like.
- 20 30 35 40 45 50
- In this position also the lower edge of the front of the cover portion completely covers the inclined or curved front of the box portion and overlaps to a certain extent the part of the front wall of the box portion which is at right angles to the base.
- Preferably the extensible hinges and fastening devices comprise each an element provided with a series of perforations, holes, slots or their equivalents and each is furnished with means for attaching it to one of the walls of the cover or box portion. This has hinged to one end a second element, which slidably carries a third element provided with a pawl, pin, tooth or its equivalent, which is adapted when the second element is lowered
- upon the first element to engage one or more of the perforations or holes, but which when the second element is raised allows the tooth or pawl to be disengaged from the hole or holes so as to enable the third element to slide with respect to the second element. The adjacent wall of the box or cover portion is connected to the outer end of the third mentioned element say by means of a hinge plate, or in some cases a spring or other hasp may be attached to the outer end of the third mentioned element, where the combined device is intended to function as the hasp of a lock. Means may be added for limiting the movement of the second element with respect to the first element to the angular displacement strictly necessary to allow the pawl, pin or the like to be lifted from the perforations, slots or the like in the first element.
- 55 60 65 70 75 80 85 90 95 100
- In order that the invention may be better understood, it will now be described with reference to the accompanying drawings in which:—
- Fig. 1 is a somewhat diagrammatic sectional side elevation of a suit case or the like constructed according to the invention with the parts arranged to give the minimum capacity.
- Fig. 2 is a similar view to Fig. 1 but with the parts arranged to give a maximum capacity, and
- Fig. 3 is a perspective view shewing the case open.
- The case shewn in the drawing has an upper portion or cover 4 and a lower portion or box 5. The top, sides, back and front of the cover are rectangular and the cover is rectangular in cross section from end to end and front to back.
- The lower or box portion 5 has a rectangular base and a rear wall 6 at right angles thereto. A short distance up, this rear wall is stepped inwards to a slight extent at 7 and then proceeds upwards parallel to the first portion at right angles to the base. The front wall 8 of the lower or box portion is at right angles to where it joins the base and for a short distance up and then it inclines or curves slightly at 9 towards the rear wall, the inclination or curvature increasing if de-

sired towards the upper edge. When the portions are assembled together to give the minimum capacity the lower edge 10 of the rear wall of the cover portion 4 comes just above the step 7 on the rear wall 6 of the box portion and the depth of the step is such that the outer exposed surfaces of the rear walls of the cover and box come in the same plane which is at right angles to the top and base of the box, case, trunk or the like.

In this position also the lower edge 11 of the front of the cover portion completely covers the inclined or curved front 9 of the box portion and overlaps to a certain extent the part of the front wall of the box portion which is at right angles to the base.

Carrying handles of any suitable type may be employed for example a single handle such as 12 may be attached to the front of the cover portion towards its lower edge and preferably so disposed that the case or the like hangs straight down when filled to a capacity midway between the minimum and maximum. In other forms the handle could be connected to the front of the box portion or two co-operating handles could be employed, one on the cover portion and one on the box portion.

Bumpers or feet 13 to a desired number may be provided on the base of the box portion 5 and also such as 14 on the rear walls of the cover and box portions. Further as the exposed portions of the rear walls come in the same plane the bumpers or feet 14 thereon can be of the same size and type.

As a general result of the construction of the box, case or the like, it stands square when rested upon the rear walls of the cover and box portions, that is to say in preferred constructions on the bumpers or feet fitted thereto.

The bumpers or feet on these rear walls also act in a known manner as protectors for the extensible hinge devices fitted to the rear walls.

In one particular method of constructing the extensible hinged or fastening device a first element 15 comprised by a channel plate is provided, closed at one end 16 and open at the other end 17. This plate, which is attached to one portion of the box, case, trunk or the like, preferably and as shown the cover portion 4, is formed or provided with a row of perforations or sets of perforations in the base (not shewn in the drawings).

A second element 18 comprising a channel plate is provided of such size that its side edges are adapted to fit between and come on the inside of the first mentioned channel plate 15. This second or inner channel plate 18 is open at one end 19 and is connected by a hinge 20 to the neighbourhood of the closed end 16 of the first mentioned channel plate 15.

Slidable on the interior of the second mentioned channel plate 18, and suitably re-

tained therein by a band or bands or the like, is a bar, strip, channel plate or the like 21 constituting the third element and furnished with a pawl, pin or the like at the inner end (not shewn), which is so formed and mounted that when the second or inner channel plate 18 is lowered into the first mentioned plate 15, the pin, pawl or its equivalent is adapted to engage with the holes or the like, whilst when the inner channel plate 18 is turned upwards upon its hinge 20 as shewn dotted in Figs. 1 and 2, the pawl or the like is brought into such a position as to be free from the perforations.

The construction is further preferably such that the inner channel plate 18 can only be turned up through a limited angle, that is through an angle sufficient to enable the third element 21 to be raised sufficiently to raise the pawl out of engagement with the hole or holes or perforations.

Either the second portion 22 of the hinge which is attached to the rear wall 6 of the box portion 5, or a spring or other hasp 23 or other required second member of such fastening device which comes at the front is also attached to the outer end of the slidable member 21 which carries the pawl, pin or the like.

With the fastening device or the like constructed as just described, where it is necessary to lengthen the said device, it is simply requisite to raise the inner channel plate 18 to a sufficient extent to enable the pawl, pin or the like to be brought out of engagement, whereupon the telescoping portion 21 can be drawn out to any required extent. On the other hand, the projecting length of the telescoping portion 21 may be reduced to suit requirements by simply pushing in the said portion, the pin or pawl slipping and engaging or locking with any desired hole or perforation when the fastener has been reduced to the required length.

The pawl, pin or the like and its co-operating slots or the like are also preferably of such character that when the pawl or the like is in engagement with the slots or the like, the extensible hinges or fastenings can only be shortened.

It is preferred to locate the extensible fastenings which come on the front walls of the box, case, trunk or the like, beneath the ends of the handle in the case where this is fastened to the cover portion, such for example as the handle 12, and as shewn on the drawings, so that the handle acts as a protector for these fastenings.

In some forms of box, case or the like a longitudinally extending strip or fillet such as 24 (shewn dotted in Fig. 2) may be attached to or form part of the body member. This fillet comes towards the upper end and fills the slight gap which otherwise might be left between the lower edge of the cover and

the upper edge of the box or body when the parts are set to give a maximum capacity.

The invention is not limited to the particular forms or details of construction described as these may be varied to suit particular cases.

What I claim as my invention and desire to secure by Letters Patent of the United States of America is:

A variable capacity box, suit case, trunk or the like, comprising a top portion of rectangular cross section from front to back and from side to side and a lower portion having a rectangular base and a rear wall at right angles thereto, said rear wall having an inwardly extending step a short distance above the base and the front wall of the lower portion being at right angles to the base at its front end and inclined slightly toward the rear wall at its upper end, the lower edge of the rear wall of the top portion bearing against the rear wall of the lower portion and above the step when the parts are assembled for minimum capacity so that the outer exposed surface of the rear walls of the top portion and lower portion are in the same vertical plane and longitudinally extensible connecting and securing means between the said portions comprising a member hingedly connected to the top portion and a member detachably connected to the lower portion at the point opposite the step.

In witness whereof I affix my signature.
ALFRED CHARLES ATKINS.
